UNITED STATES PATENT OFFICE.

GEORGE L. NIEHAUS, OF ST. LOUIS, MISSOURI.

HOT-AIR FURNACE.

SPECIFICATION forming part of Letters Patent No. 350,076, dated September 28, 1886.

Application filed January 12, 1886. Serial No. 188,252. (No model.)

To all whom it may concern:

Be it known that I, GEORGE L. NIEHAUS, of the city of St. Louis, in the State of Missouri, have invented a certain new and useful 5 Improvement in Hot-Air Furnaces, of which the following is a full, clear, and exact description, reference being had to the accompanying drawings, forming part of this specification, and in which—

10 Figure 1 is one-half in front elevation and one-half in vertical section at 1 1, Fig. 2, with the outer casing removed. Fig. 2 is a vertical section at 2 2, Fig. 1. Fig. 3 is a horizontal section at 3 3, Fig. 1, part being broken 15 away.

This furnace belongs to that class in which the smoke may be allowed to escape directly to the chimney, or may be caused to pass through a drum around which the air circulates, the air also passing upward through pipes traversing the drum.

A is the fire-pot.

B is the grate, pivoted at the center to a spider-frame, C.

20 D is a handle by which the grate may be shaken.

E is the ash-pit, having a door, F, with a register, G, as usual.

The fuel is fed through a mouth, H, having 30 a door, I, with a register, J.

K is an exit-passage in the top of the fire-pot, which leads directly into the horizontal flue L. K' is a damper in the passage K, and K² is a handle extending through the casing, 35 by which the damper may be turned. This flue L is shown extending diametrically through the apparatus. The end l has a register, L', and communicates with the outer air. The end l' of the flue L communicates with the chimney.

40 From the middle of the flue L ascends a vertical flue, M.

N is an annular flange extending outwardly and downwardly from the top of the upright flue M.

45 O is a neck extending from the top of the fire-pot and in communication with the fire-chamber by an annular passage, P, surrounding the passage K. When the damper K' of the passage K is closed, the whole of the products pass through the annular passage P and the neck O into the drum Q. As the products of combustion ascend from the neck, they im-

pinge against the deflecting-flange N and diverge to the outer parts of the drum, and finally have exit downward through the flue 55 M and the discharging end l' of the flue L.

R are a number of vertical air-pipes extending through the drum from bottom to top. The air to be heated enters the orifice S between the ash-pit and the casing T, and passes 60 upward between the casing and the fire-pot, the neck O, and around the drum Q, and through the air-pipes R in the drum, and over the drum to the exit pipe or pipes U, leading to the rooms to be heated. It will be seen that 65 the casing T incloses the ash-pit, fire-pot, neck O, and drum Q.

The operation of the apparatus is as follows: When the fire is first started, the damper K' is open, and the smoke passes directly from 70 the fire-chamber into the flue L and the chimney. After the fire begins to burn freely the damper K' may be partly or wholly closed, and then the products of combustion will pass into the drum and escape through the vertical flue 75 M and horizontal flue L into the chimney. When it is desired to lessen the heat of the furnace, the registers J and L' may be opened and the register G closed to a greater or less extent. 80

The flue L is described and shown as passing transversely through the apparatus; but this is not essential, as the parts each side of the passage K may be set at an angle to each other without materially affecting the action 85 of the flue.

I claim as my invention—

1. The combination, with the fire-chamber and the radiating-drum, of a flue communicating at one end with the smoke-flue and at 90 the other with the external atmosphere, a valve for controlling the latter communication, and a branch flue extending from the flue first named into the radiating-drum, substantially as and for the purpose set forth. 95

2. The combination, in a hot-air furnace, of a fire-chamber, passage K, with damper K', neck O, drum Q, flues L and M, and deflector N, substantially as set forth.

3. The combination, with the fire-chamber 100 and the radiating-drum having communication therewith, of a flue having communication with the said drum, fire-chamber, and the external atmosphere, and dampers for control-

ling the two latter communications, substantially as set forth.

4. The combination, with the fire-chamber, of a flue having communication with the smoke-flue, an aperture, K, through which it communicates with the fire-chamber, and an opening, l, through which it communicates with the external atmosphere, and valves or dampers

K' L', for controlling the two last-named communications, substantially as and for the purpose set forth.

GEO. L. NIEHAUS.
